AWNING FOR AUTOMOBILES

Filed Feb. 10, 1928

William A. Bracken,
BY
Geo. P. Kimmel,
ATTORNEY.

UNITED STATES PATENT OFFICE

WILLIAM A. BRACKEN, OF ELDORADO, KANSAS, ASSIGNOR OF ONE-HALF TO WILLIAM B. JONES, OF AUGUSTA, KANSAS

AWNING FOR AUTOMOBILES

Application filed February 10, 1928. Serial No. 253,502.

This invention relates to an awning structure, of the spring controlled rolling type, more especially to that class of awning structures for use in connection with doors, windows, etc., but more particularly to the doors and windows of automobiles, and an object of the invention is to provide, in a manner as hereinafter set forth, an awning structure of the type referred to which can be readily and conveniently mounted within the frame of a window or door and when so mounted can be conveniently adjusted, to position the awning body in projected relation at an angle relative to the window or door, or extended 10 in a vertical plane with respect to the window or door for shutting out light from without, and with the structure being of novel form and including means whereby the awning body is maintained taut when adjusted relative to the window or door, and further will be automatically rolled up when not in use and furthermore whereby the awning structure is so constructed and arranged that it will not in any manner detract from the 20 appearance of a window or door piece, either when the awning body is extended when in use or rolled up when not in use.

A further object of the invention is to provide, in a manner as hereinafter set forth, 30 an awning structure of the spring controlled rolling type including means to permanently maintain the awning body, when extended taut at all times.

A further object of the invention is to provide, in a manner as hereinafter set forth, an awning structure of the spring controlled rolling type, including means whereby the awning body can be employed as a shade or blind and when employed as a shade will be 40 disposed in a vertical position exteriorly of or within a vertically adjustable glass panel forming an element of a window or door now employed in automobiles, or in other words providing means whereby the awning body 45 can be adjusted at various angles with respect to the window or door to provide a canopy and also shifted to a vertical position to constitute a blind or shade arranged exteriorly or interiorly with respect to the 50 transparent panel of a window or door.

Further objects of the invention are to provide, in a manner as hereinafter set forth, an awning structure of the spring controlled rolling type, which is comparatively simple in its construction and arrangement, strong, 55 durable, compact, thoroughly efficient in its use, conveniently adjusted, not impairing in any manner the appearance of the door or window with which it is associated, readily installed with respect to a window or door 60 opening, and comparatively inexpensive to manufacture.

With the foregoing and other objects in view the invention consists of the novel construction, combination and arrangement of 65 parts as hereinafter more specifically described, and illustrated in the accompanying drawings, wherein is shown an embodiment of the invention, but it is to be understood that changes, variations and modifications can be 70 resorted to which fall within the scope of the claims hereunto appended.

In the drawings wherein like reference characters denote corresponding parts throughout the several views:

Figure 1 is a fragmentary view in vertical section of a window frame showing the adaptation therewith of a rolling awning structure in accordance with this invention and with the structure illustrated in sectional elevation.

Figure 2 is a fragmentary view in rear elevation of a window frame showing the adaptation therewith of a rolling awning structure in accordance with this invention and with the structure illustrated in rear elevation and broken away.

Figure 3 is a section on line 3—3 Figure 1.

Figure 4 is a perspective view, broken away, of the adjusting yoke for the awning body or web.

Figure 5 is a fragmentary view partly in section illustrating the coacting elements to latch the yoke in adjusted position.

An adjustable, spring controlled rolling 95 awning structure, in accordance with this invention, includes a pair of combined supporting and ratchet brackets A, only one of which is shown, a spring controlled winding roller B having its pintles supported in the 100

upper ends of the brackets A, an awning body C for winding on and off the roller B, an adjusting yoke D for and attached to the outer end of the awning body C, a pair of 5 pivots E, only one of which is shown for the arms of the yoke D, and with the brackets A and arms of the yoke D having coacting means, to be presently referred to for latching the awning body C in an extended position 10 with respect to the roller B. The brackets A are adapted to be attached to opposite side rails of and within a window frame F or to the side walls of the opening with which the awning structure is to be associated. The 15 yoke D is positioned within the window frame and has its arms completely opposing the outer side faces of the brackets.

The bracket A includes a body portion 1 provided at its top with a rearward extension 2 for the reception of the pintle 3 of the winding roller B. The body portion 1 is formed at its bottom with a rearward extension 4 formed on its outer side face with a circular boss 5 having the forward portion of 25 its forwardly directed edge provided with a set of ratchet teeth 6. The rear face of the extension 4 is provided with a concavity 6' which communicates with an opening 7 having the pivot E extending therethrough. 30 The outer end of the pivot E carries a head H and its inner end is provided with a cotter pin 9 for anchoring the pivot E to the lower portion of the bracket A. Mounted on the pivot E and positioned against the front of 35 the boss 5 is a washer 9'. The body portion 1 of the bracket is flanged as at 10 and with the flange having its upper and lower end provided with an apertured ear 11 through which extend holdfast devices 12 for anchoring the bracket A to the side rail of the frame F. The flange 10 is disposed at right angles 40 with respect to the body portion 1 and positioned adjacent the forward side edge of said body portion 1, as shown in dotted lines in 45 Figure 1.

The yoke D has its arms indicated at 13, 14 and which extends toward the pivot E. The awning body C is looped around the yoke D, as at 15 see Figure 1. The looped portion 50 of the awning body C is secured together whereby the outer end of said body C is connected to the yoke D.

Secured to each of the arms of the yoke D, in proximity to the free end of each arm, is a 55 sleeve 16, and which is riveted as at 17 to the yoke arms whereby the sleeve 16 is fixedly secured to the yoke arms, and the latter projects rearwardly from the rear end of the 60 sleeve 16, as indicated at 18.

Formed integral with the inner or rear end of the sleeve 16 at the outer side thereof, is a 65 rearwardly extending disc or plate 19 formed with a slot 20 disposed diametrically thereof. 70

65 The forward end of the slot 20 is disposed ap-

proximately at the axis of the disc or plate 19 and the latter is offset with respect to the yoke arm. The plate or disc 19 which projects beyond the free end of the yoke arm 13 is oppositely disposed with respect to the disc or plate 19 which projects beyond the free 75 end of the yoke arm 14. The disc or plate 19 is arranged to oppose the outer face of the boss 5 and the pivot E extends through the slot 20 of the disc. The washer 9' is interposed between the disc or plate 19 and the boss 5. The yoke arms 13, 14 are shiftably mounted on the pivots E and when the yoke is closed they completely oppose the outer side faces of the brackets. The free ends 18 of the yoke arms 13, 14 oppose the ratchet teeth 6 formed on the bosses 5. The free 80 ends 18 of the yoke arms 13, 14 coact with the ratchet teeth 6 for the purpose of latching the awning body C in an extended position 85 with respect to the winding roller B. The awning body C can be disposed in angular positions with respect to the frame F and can also be shifted to a perpendicular position to provide a blind. When the awning 90 body C is shifted to the desired position with respect to the frame F, the ends 18 of the yoke arms 13, 14 engage with certain of the ratchet teeth 6 and latch the awning body in the position to which it has been adjusted. 95 The controlling spring of the winding roller B maintains the awning body C taut and the yoke arms 13, 14 coact with the ratchet teeth 6 to latch the awning body C in extended 100 position with respect to the winding roller B.

It is thought the many advantages of a spring controlled, adjustable, rolling awning structure in accordance with this invention can be readily understood, and although the 105 preferred embodiment of the invention is as illustrated and described, yet it is to be understood that changes in the details of construction can be had which fall within the scope of the invention as claimed.

What I claim is:

1. In a rolling awning structure of that type including a spring controlled awning body adjusting means extendible from a window frame, a combined attaching, pivoting and latching means for an arm of said adjusting means comprising a vertically disposed supporting bracket for connection to a side rail of the window frame and having its outer side face opposing said arm throughout when said adjusting means is in closed position, said bracket having its lower end part formed with a set of forwardly directed ratchet teeth capable of being selectively engaged by the free end of said arm to latch the latter, a bodily shiftable slotted disc opposing the lower end part of said outer side face, a combined pivot and attaching element for and shiftably connecting said disc to the lower end of said bracket, and means for attach- 115 120 125 130

ing said disc to and offsetting it adjacent the free end of said arm so that when in closed position said arm will completely oppose the outer side face of said bracket.

2. In a rolling awning structure of that type including a spring controlled awning body adjusting means extendible from a window frame, a combined attaching, pivoting and latching means for an arm of said adjusting means comprising a vertically disposed supporting bracket for connection to a side rail of the window frame and having its outer side face opposing said arm throughout when said adjusting means is in closed position, said bracket having its lower end part formed with a set of forwardly directed ratchet teeth capable of being selectively engaged by the free end of said arm to latch the latter, a bodily shiftable and pivoting disc opposing the lower end part of said outer side face, means to provide a pin and slot connection between said disc and the lower end of said bracket and with the pin providing a pivot for said disc, and means for attaching said disc to and offsetting it adjacent the free end of said arm so that when in closed position said arm will completely oppose the outer side face of said bracket.

In testimony whereof, I affix my signature
30 hereto.

WILLIAM A. BRACKEN.
